TARGET UNIT FOR A BALL GAME

Frederick H. King, Ferndale, Mich.

Application June 25, 1957, Serial No. 46,727

Term of patent 14 years

(Cl. D34—5)

FIG. 1

FIG. 2

FIG. 3

Fig. 1 is a perspective view of a target unit showing my new design, as viewed laterally and from the front of such unit.

Fig. 2 is another perspective view of such unit as viewed laterally and from the rear thereof.

Fig. 3 is a top plan view of the unit.

I claim:

The ornamental design for a target unit for a ball game, as shown.
